(57) **CLAIM**

The ornamental design for a sacrocolpopexy manipulator, as shown and described.

DESCRIPTION

FIG. 1 is a front perspective view of a sacrocolpopexy manipulator according to the present invention.

FIG. 2 is a front view of the sacrocolpopexy manipulator of FIG. 1.

FIG. 3 is a rear view of the sacrocolpopexy manipulator of FIG. 1.

FIG. 4 is a left side view of the sacrocolpopexy manipulator of FIG. 1.

FIG. 5 is a right side view of the sacrocolpopexy manipulator of FIG. 1.

FIG. 6 is a top view of the sacrocolpopexy manipulator of FIG. 1; and,

FIG. 7 is a bottom view of the sacrocolpopexy manipulator of FIG. 1.

The broken lines illustrate portions of the sacrocolpopexy manipulator that form no part of the claimed design.

The sacrocolpopexy manipulator is shown with symbolic breaks. The appearance of any portion of the article between the break lines form no part of the claimed design.

1 Claim, 7 Drawing Sheets
